Filed Mar. 2, 1970, Ser. No. 21,704

Term of patent 14 years

Int. Cl. D12—16

U.S. Cl. D90—14

FIG. 1

FIG. 2

FIG. 1 is a top perspective view of a reflective bicycle pedal showing my new design.

FIG. 2 is a bottom perspective view thereof.

The diagonal lines on the side portions of the pedal denote a reflective surface.

The characteristic feature of my design is the arcuate reflective surface placed on the sides of the pedal.

I claim:

The ornamental design for a reflective bicycle pedal, as shown and described.
